UNITED STATES PATENT OFFICE

CHARLES T. BRADY, OF DETROIT, MICHIGAN

DESIGN FOR A LAMP

Application filed February 13, 1930. Serial No. 34,523. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for Lamps, of which the following is a specification, reference being had to the accompanying drawing, forming part thereof.

Fig. 2 is an elevation of the same.

I claim:—

The ornamental design for a lamp as shown.

CHARLES T. BRADY.
